CLAIM

The ornamental design for a china cabinet, as shown and described.

DESCRIPTION

FIG. 1 is a left front perspective view of a china cabinet as seen when in use, showing our new design;

FIG. 2 is a front elevational view thereof; and,

FIG. 3 is a side view the opposite side being a mirror image of the side shown.

The top, bottom and rear views are not shown and form no part of the claimed design. The dashed lines represent conventional hardware and form no part of the claimed design.
